United States Patent Office

Des. 192,797
Patented May 15, 1962

192,797

WHEEL COVER

David R. Holls, Warren, Mich., assignor to General Motors Corporation, Detroit, Mich., a corporation of Delaware

Filed Jan. 9, 1962, Ser. No. 68,235

Term of patent 7 years

(Cl. D14—30)

FIGURE 1 is a front elevational view of the wheel cover showing my new design;

FIGURE 2 is a sectional view taken generally along the plane indicated by line 2—2 of FIGURE 1;

FIGURE 3 is a side elevational view, and;

FIGURE 4 is a perspective view.

I claim:

The ornamental design for a wheel cover, substantially as shown.
